UNITED STATES PATENT OFFICE.

FRANK J. M. MILES, OF NEW YORK, N. Y., ASSIGNOR TO CHERAMY, INC., OF NEW YORK, N. Y., A CORPORATION OF NEW YORK.

DESIGN FOR A BOTTLE.

Application filed April 14, 1922. Serial No. 1,758. Term of patent 14 years.

To all whom it may concern:

Be it known that I, FRANK J. M. MILES, a citizen of the United States of America, residing at New York, in the county of New York and State of New York, have invented a new, original, and ornamental Design for a Bottle, of which the following is a specification, reference being had to the accompanying drawing, forming a part thereof.

Figure 1 shows a perspective view of a bottle embellished with this improved design of glass ornamentation.

Figure 2 is a cross section on the line 2—2 of Figure 1.

I claim:

The ornamental design for a bottle, as shown.
